SHIRT

Ralph E. Ladue, Bronxville, N. Y., assignor, by direct and mesne assignments, to Mardel Corporation, Wilmington, Del., a corporation of Delaware

Application April 8, 1937, Serial No. 135,636

5 Claims. (Cl. 2—269)

This invention relates to improvements in shirts and has particular reference to improvements in the sleeve structure thereof.

At the present time it is necessary for stores to stock shirts of various sleeve lengths for each size, which not only represents a large inventory and investment, but requires an enormous amount of additional space. Also, the lengths of the sleeve are not always uniform as to indicated lengths, owing to difference in cut, abnormally wide or narrow shoulder width of the wearer, and the like.

In accordance with the present invention, a shirt is provided in which the cuff is furnished separately for permanent attachment to the end of the sleeve after the latter has been trimmed to the proper length to provide the over-all sleeve length desired or required by the purchaser, the sleeve of the shirt as manufactured being of a maximum length adequate to meet the standard sleeve length requirements of the trade. The various standard sleeve lengths are indicated on the elongated sleeve or the sleeve is measured in accordance with the measurement of the wearer, and then trimmed accordingly. The cuff is permanently attached by a suitable launderproof adhesive or cement, or is otherwise permanently attached in the store by a very simple operation.

It will be seen that with the present invention, only one size shirt is provided in each neck-band size and style and the sleeve length is conformed to fit the wearer, whether his arms are abnormally long or short or whether or not he requires half-sizes, the cuff being attached to the sleeve in the store in a few minutes. This not only means a better fit for the wearer and no difficulty in locating special sleeve lengths, but also results in a saving of manufacturing and inventory costs, and material reduction of the stocking space.

For a more complete understanding of the invention, reference may be had to the accompanying drawings, in which:

Figure 1 illustrates the cuff and sleeve arrangement before permanent association according to the present invention;

Fig. 2 is a cross-section therethrough as seen along the line 2—2 of Fig. 1;

Fig. 3 illustrates the finished sleeve;

Figs. 4 and 5 illustrate in perspective a preferred arrangement for attaching the cuff and sleeve, these figures showing the parts before and after attachment, respectively;

Fig. 6 illustrates in perspective a French style cuff attached to the sleeve in a different way;

and

Figs. 7 and 8 illustrate the method of attachment of the arrangement of Fig. 6, these figures showing the parts before and after attachment, respectively.

Referring to Fig. 1 of the drawings, numeral 10 designates the sleeve of a shirt which is constructed in the usual way except that the sleeve is not provided with a cuff and is of a length equal to the maximum sleeve length less the effective width of the cuff. The inside surface of the sleeve 10 is printed or otherwise marked with dimension lines 11 spaced $\frac{1}{2}$ inch apart and with dimension numerals 12 indicating the corresponding sleeve length less the effective width of the cuff. The dimension marks 11 do not indicate the length of the cuffless sleeve, but rather, indicate the finished over-all length of the sleeve after the cuff has been attached thereto. The sleeve measurement is made from a predetermined point on the body of the shirt and this point customarily is at the center of the top of the shirt back, i. e., the middle of the base of the collar or approximate rear collar button position. Accordingly, the sleeve length is the distance from this point to the end of the sleeve, which is the outer edge of the cuff. Thus, to accommodate the usual trade requirement for a maximum sleeve length of thirty-seven inches, a shirt is provided according to this invention in which the actual distance from the center of the shirt back at the base of the collar to the thirty-seven inch mark on the sleeve is thirty-seven inches less the effective width of the cuff, i. e., the total width of the cuff minus the overlap between the inner edge of the cuff and the extremity of the sleeve. These dimension marks 11 may be $\frac{1}{2}$, $\frac{1}{4}$ or $\frac{1}{8}$ inch apart, depending upon requirements, and are printed in ink which disappears on first washing of the shirt. Numerals 12 are similarly of an ink which is not fast.

The cuff 13, which may be either round or French, is preferably constructed at its upper edge as indicated in Figs. 1 and 2, that is, the upper edges of the two layers of the cuff material are turned inwardly and stitched together and to the corresponding layers at 14 so that the upper edge of the cuff is provided with a slot 15 that is generally V-shaped. The lower edge 16 of the cuff is formed in the usual way and the cuff may be provided with stiffening material or not, as required. As shown, particularly in Fig. 1, the lateral edges of the cuff 13 are stitched at 17 so that slot 15 is closed at its ends, forming a pocket. The width of the cuff 13 is $\frac{1}{8}$ inch to $\frac{1}{4}$ inch greater than the width of the sleeve 10.

so that the end of the sleeve may be readily inserted within the slot or pocket 15.

In the preferred arrangement for permanently fastening the cuffs to the trimmed ends of the sleeves, the inner sides of the slot 15 of the cuff 10 are evenly coated with a thin film of suitable thermoplastic cement which, when set, is not susceptible to deterioration by water, soaps, and other cleaning compounds, or to oxidation such that it loses its flexibility and adhesion. Merely by way of example, the thermoplastic coating 18 may comprise cellulose-acetate, or nitrate, and a compatible thermoplastic resin or the like, such as a vinyl resin or other synthetic resin or other plasticizer.

Instead of applying the adhesive or adhering material or cement directly to the inner surfaces of the slot or pocket 15 of the cuff 13, the cuff may be constructed as illustrated in Figs. 4 and 5, 20 in which the upper edges of the outer fabric layers of the cuff are turned inwardly at 19 and there is stitched to each of them an adhesive sheet 20 and the outer layers of the cuff and these adhesive sheets are then stitched together 25 at 14', again forming the V-slot 15. The adhesive sheet 20 preferably comprises a woven, knitted or other fabric composed of or containing artificial filaments of cellulose derivative such as cellulose-acetate, ethyl-, methyl-, or benzyl-acetate, nitro-cellulose, or other ester of cellulose or mixture thereof, having deposited thereon a suitable non-volatile plasticizer, which upon application of heat and pressure softens the cellulose fiber so that it fuses and adheres to the joining fabric 30 surfaces and threads.

In both forms of the invention illustrated in Figs. 1 and 2, or 4, the end 21 of the sleeve 10 is inserted within the pocket 15 and the proper degree of heat and pressure applied to the joint 40 so that the cementitious material 18 or 20 softens and fuses to and between the meshes of the side walls of the slot 15 of the cuff 13 and the sleeve 10, uniting the sleeve to the cuff with a permanent and secure bond which is launderproof and 45 not broken down or deteriorated by repeated washings, oxidation, or contact with any of the ordinary washing or cleaning fluids or the like to which a shirt is subjected in ordinary use. The cementing agent is so selected that the joint 50 is flexible and remains flexible so that it preferably does not materially increase the stiffness of the cuff when starch or other stiffening material or processes are employed.

Inasmuch as the greatest strain on the joint 55 occurs at the upper corner of the cuff, the stitching 17 is preferably carried to its upper edge, as shown in Fig. 1, so that any strain on the upper corner of the cuff is applied to the stitched joint rather than to the cemented joint, although for 60 ordinary use the cemented joint has been found to be sufficiently strong, and unless the additional precaution is deemed necessary, the slot 15 need not be pocket-shaped, i. e., stitching 17 need not be carried beyond the bottom of the pocket or 65 slot 15 and the cuff 13 may be made the same width as the sleeve 10.

Where even greater strength is required at the upper corner of the cuff, the cuff may be cemented to the sleeve, as described, and metallic self-locking fasteners 22, such as are illustrated in Figs. 6, 7 and 8 may be employed. These fasteners 22 are formed of pliable non-oxidizing or non-corrosive metal, which is proof against deterioration by the usual laundering fluids and common 75 pounds, and comprises a male portion 23 hav-

ing two prongs 24 which are adapted to be engaged and spread by the center portion 25 of the female fastening element 26 so that as the parts 23 and 26 are forced together the prongs 24 are spread apart by 25 and forced laterally into the curved portions 27 of part 26 so that they become locked therein as indicated in Fig. 8 when the fastener 22 is completely closed.

These fasteners 22 are preferably so constructed and of such a size as to be inconspicuous 10 and have no projecting corners or edges upon which objects can catch, which would distort the fasteners or tear the cloth. Other suitable permanent fastening means may be employed if desired.

The individually-measured feature of the sleeve of this invention comprehends the association of a sleeve, of selected length according to the arm length of the wearer, and the cuff in the manner described. Each neckband size and style shirt 20 is provided with the same maximum length sleeve with cuff detached and the prospective wearer is either measured to determine the proper sleeve length or indicates the desired sleeve length in inches and fractions thereof. In the store the 25 sleeve 10 is trimmed along the proper selected dimension line 11 and the end 21 of the trimmed sleeve is inserted in the slot 15 of the cuff 13, which is then permanently secured to the sleeve by the application of heat and pressure in the 30 manner described, or by other permanent fastening means, so that the cuff becomes an integral part of the sleeve, remaining permanently attached thereto. Other fastening means, such as stitching, may be provided but the methods described have been found satisfactory inasmuch as the application of the cuff to the sleeve requires merely the use of a hot iron or specially provided heating tool, whereby the proper degree of 35 heat and pressure may be applied to the parts in 40 the manner described to secure the permanent attachment.

Accordingly with the arrangement of the present invention, the manufacturer provides only one neckband size shirt in each style with the 45 corresponding cuffs, whereby manufacturing and inventory costs and stocking space, with its attendant costs, are saved and the wearer is provided with a perfect fit in so far as sleeve length is concerned, even to fractions of inches.

Also if desired, each shirt may be provided with either detached round or French cuffs, as 50 illustrated in Figs. 3 and 6, or with both, so that the wearer may select as between the two, thus effecting another saving in cost and stock of 55 shirts with both kinds of cuff.

While certain preferred embodiments of the invention have been illustrated and described herein, it is to be understood that the invention is not limited thereby but is susceptible of variations of form and detail within the scope of the appended claims. Thus other cements or adhesives softenable by heat, solvents or the like, or other permanent fastening means and methods may be employed, so long as the cuff, once 60 attached to the trimmed sleeve, permanently 65 remains an integral part of the sleeve.

I claim:

1. The method of manufacturing shirts, which comprises first forming a completed shirt but devoid of cuffs and having the sleeves thereof permanently attached at the shoulder end to the body of the shirt and formed of a predetermined length adequate to meet the standard sleeve length requirements of the trade, separately form- 70 75 80 85 90 95 100

- ing completed cuffs of a predetermined width for the sleeves, subsequently trimming the sleeves at the cuff end at a point measured from a predetermined point on the shirt body and corresponding to the finished sleeve length less the effective width of the cuffs, and then permanently attaching the preformed cuffs to the ends of the sleeves so trimmed to produce a shirt having sleeves of predetermined over-all length.
- 10 2. The method of manufacturing shirts, which comprises first forming a completed shirt but devoid of cuffs and having the sleeves thereof permanently attached at the shoulders and formed of a predetermined length adequate to meet the standard sleeve length requirements of the trade, providing spaced dimension markings on the ends of the sleeves equal to a finished sleeve length less the effective width of the cuff and indicating the various sleeve length dimensions according to the requirements of the trade, separately forming cuffs for the sleeves, trimming the sleeves at a selected marking thereon corresponding to the predetermined sleeve length for the wearer, and then permanently attaching 25 the said cuffs to the ends of the sleeves so trimmed to produce sleeves corresponding in over-all length to that indicated by the selected marking.
3. As a new article of manufacture, a completed shirt ready for sale and having sleeves permanently attached at the shoulders but devoid of cuffs and of a predetermined length adequate to meet the standard sleeve length requirements of the trade, and a pair of separate, preformed
- cuffs of predetermined effective width for permanent attachment to the ends of the said sleeves after the latter have been trimmed to conform to the predetermined sleeve length of the wearer.
4. As a new article of manufacture, a completed shirt ready for sale but devoid of cuffs and having sleeves of a predetermined length adequate to meet the standard sleeve length requirements of the trade, said sleeves having transverse dimension marks spaced from the ends thereof and indicating the location where the sleeve is to be trimmed to form the standard sleeve length desired, and a pair of separate, completed cuffs of predetermined effective width adapted to be permanently secured to the ends of the said sleeves after the latter have been trimmed off transversely at one of said marks corresponding to the predetermined sleeve length desired to produce completed sleeves corresponding in over-all length to the standard sleeve 20 length indicated by the mark at which the sleeves were trimmed.
5. As a new article of manufacture, a completed shirt having sleeves permanently attached at the shoulders thereof but devoid of cuffs and of a predetermined length adequate to meet the standard sleeve length requirements of the trade, a pair of separate completed pre-formed cuffs of a predetermined effective width, and means on said cuffs for permanently attaching the said cuffs to the ends of the corresponding sleeves after the latter have been trimmed to conform to the predetermined sleeve-length of the wearer.

RALPH E. LADUE.
